UNITED STATES PATENT OFFICE.

EVERISTE JOSEPH DURAND, OF CHEROYGAN, MICHIGAN.

THREAD-HOLDING DEVICE.

1,035,559.

Specification of Letters Patent. Patented Aug. 13, 1912.

Application filed July 6, 1911. Serial No. 637,232.

To all whom it may concern:

Be it known that I, EVERISTE J. DURAND, a subject of the King of England, residing at Cheboygan, in the county of Cheboygan and State of Michigan, have invented certain new and useful Improvements in Thread-Holding Devices; and I do hereby declare the following to be a full, clear, and exact description of the invention, such as will enable others skilled in the art to which it appertains to make and use the same.

This invention relates to new and useful improvements in thread holding devices.

An object of this invention is the provision of a receptacle, in which is located a rack adapted to support balls of twine or the like, the said receptacle being provided with suitable means for guiding the thread through one wall thereof whereby the said thread, after passing through the wall, may be wound to form a thread of greater thickness than the individual threads.

Another object of this invention is the provision of an apparatus to be used for holding wax ends, the said threads adapted to be supported in such manner that they may be severed in equal lengths.

A further object of this invention is to improve and simplify devices of this character, rendering them comparatively simple and inexpensive to manufacture, reliable and efficient in use, and readily operated.

With the above and other objects in view, this invention resides in the novel features of construction, formations, combinations and arrangements of parts to be hereinafter more fully described and claimed, and illustrated in the accompanying drawings, in which—

40 Figure 1 is a longitudinal sectional view of my improved invention; Fig. 2 is a vertical section through the same, and Figs. 3, 4 and 5 are detailed views of the same.

Referring to the drawing by characters of reference, the numeral 1 designates generally my improved apparatus, which consists of a receptacle 2, comprising offset side walls 3 and 4, connected at their extremities by end walls 5. The side walls 3 and 4 are slightly less in height than the end walls 5, while the wall 4 has secured thereto an inwardly extending supporting ledge 6, upon which are located guides 7, the purpose of which will be later disclosed.

55 A pair of uprights 8 are secured to the opposite end walls 5, and support upon their

upper ends a pair of rails 9, the upper edges of which are beveled inwardly, as indicated by the numeral 10 for engagement with the lower tapered edge 11 of a movable bar 12, 60 which is hinged, as indicated by the numeral 13, to the opposite end walls 5 of the receptacle 2.

A partition 13' is slidable in slots 14 formed in the inner face of the end walls 65 5, adjacent the side or rear wall 3 of the receptacle, and is held against displacement by wedge blocks 15, which are adapted to be inserted into the slots 14 for engagement with the upper edges of the partition 13', 70 which obviously prevents its displacement. The upper edge of the partition 13' is corrugated, as indicated by the numeral 16, and is connected with the rear wall 3 at intervals throughout its length by spaced 75 parallel rods 17, between which and the inner faces of the wall 3 and partition 13' are loosely held spools 18 of thread or the like.

The free ends of the thread are passed between the rails 9 and bar 10, and are extended through the guides 7, which consist of a pair of inwardly convexed plates 19 and 20, the former of which is rigidly secured to the supporting ledge 6, while the latter is slidably located upon a pin 21, which passes concentrically through the plate 19, and is normally forced thereagainst by means of a tension spring 22, which surrounds the pin 21, with its offset ends bearing against a collar 23, slidably located upon the said pin 21, and limited in its upward movement by the head 24 thereof and the upper concaved face of the plate 20. As the thread is passed between the plates 19 and 20, these said plates will be yieldingly forced into engagement with the threads, which provides a means for regulating the ease with which the thread may be drawn from the receptacle.

100 A suitable cover or closure 25 is hinged, as indicated by the numeral 26, to the upper edge of the rear wall or side 3 of the receptacle, and is provided upon its opposite ends with extensions 27 and 28, the former of which is adapted to abut against the rear edges of the ends 5, while the latter is adapted to abut against the forward edges of the ends 5 and be held slightly in spaced relation above the upper edge of the front wall 4, which serves to permit the 105 passage therethrough of the above-mentioned threads. The closure 25 may be

locked to the receptacle by means of turn buttons 29, or any other suitable means.

From the foregoing disclosure it will be manifest that when spools of thread have been placed in the rack and the ends thereof passed between the rails 9 and bar 12 and through the guides 7, extended through the front of the cabinet, and wound together, that sections of the thread may be severed, 10 each of which will be of equal length.

From the foregoing disclosure, taken in connection with the accompanying drawings, it will be manifest that a thread holder of the nature described is provided for 15 which will fulfil all of the necessary requirements of such a device.

Having thus fully described this invention, what I claim as new and desire to protect by Letters Patent is:

20 A device of the nature described comprising a receptacle, a partition located

therein, rods connecting the said partition with one wall of the receptacle, forming a rack for the support of spools of thread, rails supported within the receptacle, a 25 hinged bar removably engaging the rails, whereby the said thread will be prevented from tangling, pins mounted within the receptacle, stationary plates engaging the pins, 30 slideable plates located upon the pins, springs carried by the pins and forcing the slideable plates into engagement with the stationary plates, whereby tension will be exerted upon the thread in passing between the plates, and a closure for said receptacle.

35 In testimony whereof I affix my signature in presence of two witnesses.

EVERISTE JOSEPH DURAND.

Witnesses:

SADIE SPENCER,
THOMAS S. McGINN.
